UNITED STATES PATENT OFFICE.

JULIUS J. VERNIER, OF TOLEDO, OHIO

CATAMENIAL SACK.

SPECIFICATION forming part of Letters Patent No. 467,963, dated February 2, 1892.

Application filed April 7, 1891. Serial No. 387,932. (No model.)

To all whom it may concern:

Be it known that I, JULIUS J. VERNIER, a citizen of the United States, residing at Toledo, in the county of Lucas and State of Ohio, have invented a new and useful Menstrual Receptacle, of which the following is a specification.

This invention is an improvement in menstrual receptacles, and has for its objects to produce a menstrual receptacle which will be adjustable to vaginas of different lengths, to produce a receptacle the wearing of which will occasion little or no inconvenience, and, furthermore, to produce a menstrual receptacle which will be practical, cleanly, inexpensive, and efficacious.

With these objects in view the invention resides in the various novel details of construction and in the combination of parts hereinafter fully described, and particularly pointed out in the claim.

In the drawings, in which I have illustrated my invention, and in which like letters of reference indicate corresponding parts, Figure 1 is a perspective view of the device. Fig. 2 is a central vertical section of it.

In the drawings, the letter A designates my device, which consists of the receptacle proper A' and the tube portion A². The receptacle proper A' consists of a flexible and elastic sack a, which has upon its open end the elastic rim a'. This receptacle may be made of rubber, cloth rendered impervious to liquids, or any suitable textile fabric. The tube portion A² consists of a cup a², a tube a³, extending from the bottom of said cup, a tube a⁴, adapted to fit and inclose the tube a³, and an enlargement upon the lower end of the tube a⁴. This enlargement (indicated by the letter a⁵) has upon its periphery an annular groove a⁶, in which the elastic rim a' of the receptacle proper A' is adapted to fit, and thereby to support the said receptacle.

I construct the tube portion A² of elastic material and may line it or the receptacle proper with suitable absorbents.

The cup a² is intended to be inserted within

the vagina and to receive the neck of the womb, the menstrual discharge being guided directly from the cup through the tubes a³ and a⁴ into the receptacle A'. The object of providing the telescoping tubes a³ and a⁴ is to accommodate the device to women of different sizes, the cup resting against the neck of the womb and the enlargement a⁵ fitting close up against the labia. As the parts are flexible, they will accommodate themselves to the movements of the wearer and cause no pain, irritation, or inconvenience. The telescoping tubes a³ a⁴ may be provided with stops or similar devices to prevent them from separating, if it should be thought necessary.

In use the tube portion A² is inserted within the vagina, as above described, and the receptacle A' attached thereto by springing the rim a' into the annular groove a⁶. When the receptacle is full, it may be detached from the tube portion and emptied.

Having thus fully described my invention, what I claim as new, and desire to secure by Letters Patent, is—

In a menstrual receptacle, an upwardly-extending tube terminating at its lower end in an enlarged annular head or flange provided on its periphery with a surrounding annular groove, a supplemental tube terminating at its upper end in a womb-receiving cup and adapted to adjustably engage and telescope within said upwardly-extending tube to allow for the various depths of vagina, and an elastic sack or bag provided around its upper edge with a stiffened elastic rim that is adapted to detachably engage said annular groove in said head or flange, which flange or head is further designed to fit and rest close up against the labia, substantially as specified.

In testimony that I claim the foregoing as my own I have hereto affixed my signature in presence of two witnesses.

JULIUS J. VERNIER.
